UNITED STATES PATENT OFFICE.

MILLER REESE HUTCHISON, OF LLEWELLYN PARK, NEW JERSEY, ASSIGNOR, BY MESNE ASSIGNMENTS, TO ACOUSTIC PRODUCTS COMPANY, OF NEW YORK, N. Y., A CORPORATION OF DELAWARE.

SOUND-REPRODUCING DEVICE.

Application filed April 29, 1927. Serial No. 187,427.

This invention relates to sound reproducers and more particularly to reproducers of the electromechanical type in which a mechanical diaphragm is operated by an electromagnetic unit.

In order to insure an accurate and undistorted reproduction of sound in an apparatus of the above type, it is essential to maintain a fixed and predetermined spacing between the armature and pole pieces and to prevent excessive stresses from being set up within the elements themselves.

This is accomplished, in accordance with the present invention by mounting the elements on a yieldable support so that any variations in the stress of the link connecting the armature to the diaphragm will automatically be relieved by movement of the entire unit. Excessive stresses are therefore prevented from being set up within the electromagnetic unit or in the element connecting said unit to the diaphragm whereby any variations due to deformation, shock, temperature changes, or other causes will be automatically compensated for and prevented from producing strains or disturbing the spacing of the various parts.

The stationary portion of the electromagnetic reproducing unit such as the pole pieces may be yieldably supported on a fixed framework and the vibrating element or armature may be operatively connected to the diaphragm by any suitable means. The stationary portions are constructed so as to have a moment of inertia sufficiently great to prevent movement thereof at audio frequencies in response to the usual operating forces and should have a free period of vibration at a frequency below audibility whereby movement at audible frequencies will be still further opposed. Vibrations at these frequencies are thus executed practically entirely by the armature and transmitted thereby to the diaphragm. The unit is however, freely movable in response to applied shocks and consequently will automatically take up any stresses which may be introduced into the parts either by shocks, warping of the diaphragm, temperature changes or other conditions of use.

The invention is particularly applicable to loud speaking devices having comparatively large diaphragms such as the so-called cone type loud speaker, but may however, be

applied to other cases where it is desired to vibrate a flexible diaphragm by electromagnetic means which may take the form of a polarized relay or a push and pull type relay such as those commonly used in telephone receivers. Such relays are constructed with a vibrating armature which is connected to the flexible diaphragm by a suitable link whereby the vibrations of the armature may be imparted to the diaphragm.

The invention also consists in certain new and original features of construction and combinations of parts hereinafter set forth and claimed.

Although the novel features which are believed to be characteristic of this invention will be specifically pointed out in the claim appended hereto, the invention itself, as to its objects and advantages, the mode of its operation and the manner of its organization, may be better understood by referring to the following description taken in connection with the accompanying drawing forming a part thereof, in which like reference characters have been used to denote like parts in the various figures. Since such illustration is, however, primarily for purposes of disclosure, it will be understood that the structure and the method of operation thereof may be modified in various respects without departing from the broad spirit and scope of the invention.

One embodiment of the invention has been shown for purposes of illustration in the accompanying drawing, in which

Fig. 1 is a diagrammatic view of the reproducing device constructed in accordance with this invention; and

Fig. 2 is an enlarged detail view of the unit and flexible support, and

Fig. 3 shows the invention applied to a cone type loud speaker.

In the following description and in the claim the various details of the apparatus and the various steps in the process will be identified by specific means for convenience, but they are intended to be as generic in their application as the art will permit.

Referring to the figures more in detail, the invention is shown as comprising a diaphragm 10 which is capable of vibrating at audio frequencies, and is attached by suitable means to fixed supports 11. An elec-

tromagnetic reproducing unit 12 which may be of any well known form such as for example that having a movable armature and stationary pole pieces, the details of construction thereof forming no part of the present invention, is rigidly secured to a mass 13 which may constitute a separate metallic block or may be included as a part of the stationary portion of the unit. It has been shown as a separate element for purposes of illustration only. The unit 12 may be supported by a flexible member 14 from a support 11, the flexible member providing for relative movement between the unit and the support. The movable element or armature of unit 12 may be connected to diaphragm 10 by suitable means, such as link 15 whereby the vibrations of the armature are transmitted to and reproduced by the diaphragm itself.

The mass of the stationary portion of the unit or pole pieces should be such that its moment of inertia is sufficiently large to prevent movement thereof at audio frequencies in response to applied impulses and to cause such movement to be executed by the diaphragm. Furthermore, the natural period of vibration of the electromagnetic unit should be at a frequency below audibility. Any warping of the diaphragm, therefore, which takes place slowly will cause a corresponding movement of the unit due to the flexure of the link 14, and any mechanical variations in the size of the parts due to changes in temperature will also be compensated for by the same means without imposing an excessive stress upon link 15. Furthermore, any jars or shocks, which would tend to distort the various parts will cause a simultaneous movement of the unit and diaphragm and prevent injury to either element.

In the reproduction of sound waves, the armature of electromagnetic relay 12 will be vibrated in response to the applied varying electric current of various audio frequencies. The moment of inertia of the pole pieces will prevent movement in response to such audio frequency vibrations and will cause such vibrations to be transferred through link 15 to diaphragm 10. It is obvious, therefore, that the size of mass 13 must be such that it will be more difficult to cause

movement of the pole pieces than of the diaphragm at audio frequencies, whereby the unit will remain substantially stationary while audio frequency vibrations are being set up in the diaphragm.

Referring to Fig. 2, the principles of this invention are shown as applied to a cone type loud speaker of well known construction comprising a standard 20 and movable diaphragm 21 attached thereto. The elements corresponding to those in Fig. 1 are given similar reference numerals and operate in a similar manner. Link 15 in this case is however, shown as connecting the armature of unit 12 with the apex of cone shaped diaphragm 21.

In accordance with the present invention any distortion of the diaphragm or of the support will be immediately compensated for without injury to any of the elements by movement of the electromagnetic unit. The adjustment of the diaphragm with respect to the pole pieces, therefore, having once been determined upon may be maintained constant, and the stress upon link 15 may be prevented from increasing to an undesirable value. The size of the parts may, therefore, be reduced and the danger of damage in handling may be practically eliminated. Furthermore, a better tonal quality is insured inasmuch as the adjustment of the armature is not altered nor unusual stresses set up therein.

While certain novel features of the invention have been shown and described and are pointed out in the annexed claim, it will be understood that various omissions, substitutions and changes in the forms and details of the device illustrated and in its operation may be made by those skilled in the art without departing from the spirit of the invention.

What is claimed is:

A sound propagating device comprising a diaphragm, a retaining structure for said diaphragm, an actuating unit for said diaphragm and flexible means for supporting said actuating unit from said retaining structure.

Signed at New York in the county of New York and State of New York this 28 day of April A. D. 1927.

MILLER REESE HUTCHISON.
